UNITED STATES PATENT OFFICE.

CHESTER S. JENNINGS, OF BOSTON, MASSACHUSETTS, ASSIGNOR, BY MESNE ASSIGNMENTS, TO AMERICAN PNEUMATIC SERVICE COMPANY, OF BOSTON, MASSACHUSETTS, A CORPORATION OF DELAWARE.

PNEUMATIC-DESPATCH-TUBE APPARATUS.

1,137,327.

Specification of Letters Patent. Patented Apr. 27, 1915.

Application filed July 11, 1907. Serial No. 383,176.

To all whom it may concern:

Be it known that I, CHESTER S. JENNINGS, a citizen of the United States, residing at Boston, in the county of Suffolk and State 5 of Massachusetts, have invented certain new and useful Improvements in Pneumatic-Despatch-Tube Apparatus; and I do hereby declare the following to be a full, clear, and exact description of the invention, such as 10 will enable others skilled in the art to which it appertains to make and use the same.

The invention relates to pneumatic despatch tube apparatus, and more especially to 15 mechanism controlling the passage of air through the system in such manner that air passes only when carriers are being transmitted between stations.

The primary object of the invention is to 20 provide mechanism for controlling the passage of air through the transit tubing which shall be simple in construction, and which will act in a uniform and reliable manner under the varying conditions which arise during the use of the system.

25 One of the features of the invention consists in providing transit tubing, in which there is a plurality of despatch stations, with an air valve for controlling the passage of air through the tubing and operating the 30 valve by mechanism the action of which is not dependent upon the pressure in the system, and which acts to automatically open the valve when a carrier is despatched from any station, and to automatically close the 35 valve after sufficient time has elapsed for the carrier to be transmitted to its destination. The valve is thus open only when a carrier is to be transmitted from one or all of the stations, and the period during which 40 the valve remains open may be reduced to a minimum since the action of the controlling mechanism is unaffected by variations in the pressure in the system such as may be caused by an increase in the number of carriers in 45 transit at the same time. Consequently the mechanism which produces the flow of air through the system may act in a highly efficient manner and with a minimum consumption of power.

50 Further features of the invention relate to the construction of the timing mechanism for controlling the closing of the valve.

The various features of the invention will be understood from an inspection of the ac-

companying drawings in which Figure 1 is 55 an elevation showing diagrammatically an apparatus embodying the invention, and Fig. 2 is a sectional detail showing the air valve and controlling mechanism.

In the apparatus illustrated in the drawings the transit tube A for transmitting carriers from a central station to a sub-station is provided with an open bell-mouth so that the carrier may be readily introduced into the tube by the cashier or other person 60 at the central station. This tube leads to the terminal C at the sub-station, which is of the usual construction, and is provided with a suitable valve c for closing the opening through which the carrier is discharged. 65 The transmission tube B for transmitting the carriers from the sub-station to the central station is connected with the terminal C in the usual manner, and is provided with a carrier inlet opening which is normally 70 closed by the usual valve or door E. The delivery end of the transit tube B is connected with a terminal D which is provided with a carrier discharge opening through which 75 the carrier is delivered at the central station. 80 This opening is normally closed by a door or valve d of usual construction. The means for causing air to flow through the transit tubing comprises a vacuum or suction drum F, which communicates with the terminal D 85 through tubes G G¹ and a valve casing H introduced between said tubes. The valve casing is divided horizontally into two chambers h h¹ by a partition H', and the pipes G G¹ communicate respectively with 90 the chambers h h¹. An opening h² is formed through the partition H' and the communication between the chambers h h¹ is controlled by means of an air valve I. When 95 the valve is closed there is no communication between the transit tubing and the suction or vacuum drum F, and there is no passage of air through the transit tubing. When the valve I is opened the transit tubing is connected through the pipes G¹, valve casing H, and pipe G with the suction drum, and air passes through the transit tubing until 100 the valve is closed.

The air valve is held normally closed by a spring J the tension of which may be varied 105 to suit the conditions under which the apparatus is operating by means of a nut K against which the upper end of the spring

bears. The mechanism for opening the valve comprises a solenoid L, the armature L¹ of which is connected with a valve operating lever M. The lever M is connected 5 with the rod I' on which the valve I is secured by means of a pin and slot connection i. The solenoid L is energized to open the air valve whenever a carrier is introduced into the transit tubing at any of the stations 10 therein. For this purpose circuit closing devices are provided at each station, which are operated to open and close the solenoid circuit when a carrier is introduced into the transit tubing. 15 The circuit closing devices for the central station comprise contacts N which are included in the solenoid circuit. A switch arm N' is arranged at the mouth of the tube A and is provided with a contact piece N² arranged 20 to engage the contacts N and close the solenoid circuit. The switch lever is held normally with the contact arm N² out of engagement with the contacts N, so that the solenoid circuit is normally open at this 25 point. When a carrier is introduced into the mouth of the tube A it swings the switch lever N' so as to engage the contact arm N² with the contacts N and close the solenoid circuit. The solenoid is thus energized and 30 acts to open the air valve so that a suction is created in the transit tubing which causes the carrier to travel through the tubing. As soon as the carrier passes the switch lever N' the lever returns to normal position, thus 35 breaking the solenoid circuit and deenergizing the solenoid so that the air valve is released and may close under the influence of the spring J and the controlling mechanism to be described. 40 The circuit closing and opening devices for the sub-station are similar to the devices just described, and consist of contacts N³ in the solenoid circuit which are arranged to be engaged by a contact arm N⁴ connected 45 with the door E which closes the carrier receiving opening in the tube B. When the door E is open to insert a carrier the solenoid circuit is closed and the air valve opened. When the door is closed after introducing 50 a carrier into the transit tubing, the solenoid circuit is broken at this point and the valve is free to close under the influence of the spring J and controlling mechanism. 55 The means for controlling the closing of the valve so that it may remain open during the time required to transmit the carrier from one station to another comprises a controlling chamber O formed within the casing H and provided with a movable wall O' which is connected with a downwardly projecting extension I² of the valve rod I'. The 60 movable wall of the controlling chamber is preferably in the form of a flexible diaphragm which may move toward and from the opposite wall of the chamber to accom-

modate the movements of the valve I. The controlling chamber is provided with an air inlet o in which the checking valve o' is mounted in such manner that air may enter freely through the air inlet but passage of air in the opposite direction is prevented. In the construction shown the check valve is in the form of a small ball mounted in a valve chamber formed in the air inlet. The controlling chamber is also provided with a restricted outlet or vent o² through which the air within the chamber may escape during the closing of the valve I. The flow of air through this vent may be regulated by means of an adjustable valve or screw o³. 80

When the air valve I is open the diaphragm O' is moved upward and during this upward movement of the diaphragm air is freely admitted to the controlling chamber O through the air inlet o and check valve o'. 85 When the solenoid is deenergized and the valve is released the closing of the valve is opposed by the air within the regulating chamber O and the time during which the valve is open will depend upon the time required for the air within the regulating chamber to escape through the vent o². The size of this vent may be regulated so that the air valve will remain open for such period as may be required to transmit a carrier 95 from one station to another in the transit tubing. 90

While I have shown the invention embodied in an apparatus in which the air valve is arranged between the transit tubing and the means for producing a flow of air through the tubing, since certain features of the invention relate more particularly to such an apparatus, it will be understood that so far as certain other features of the invention are concerned, and especially those features relating more or less to the specific form of valve controlling devices, the invention may be embodied in systems in which the air valve is otherwise located, and in which a part or all of the transit tubing is in constant communication with the suction drum or other means for causing air to flow through the tubing. 100 105 110

Having set forth the nature and object of the invention, and described one form of apparatus in which it may be embodied, what I claim is:—

1. In pneumatic despatch tube apparatus, a transit tube for the transmission of carriers, an air-exhaust pipe communicating with said transit tube, a casing interposed in the communication between the transit tube and air-exhaust pipe, a partition dividing said casing into two chambers respectively communicating with the transit tube and the exhaust pipe and said partition having an opening between the two chambers, a valve controlling said opening between the two chambers, a spring normally closing 115 120 125 130

said valve, a lever pivoted on the exterior of the casing and connected with said valve, a solenoid having its armature connected with the free end of said lever; an electric circuit including said solenoid, a normally open switch actuated by the insertion of a carrier in the transit tube to momentarily close the electric circuit to energize the solenoid so that the movement of its armature through the intervening mechanism will open said valve to permit the flow of air through said chambers from the transit tube to the exhaust pipe, a diaphragm connected with said valve positioned in the casing chamber communicating with the exhaust pipe and forming with the wall of such chamber a controlling chamber, said controlling chamber having an air inlet to admit outside air when the diaphragm rises through the opening of said valve by the solenoid and said controlling chamber having a restricted vent to permit the egress of air when the diaphragm lowers through the closing of the valve by said spring, a check-valve to prevent the egress of air through said air-inlet of the controlling chamber, and a screw-valve to regulate the egress of air through said restricted vent of the controlling chamber to retard the closing of said valve through the action of the spring.

2. A pneumatic despatch tube system, having, in combination, transit tubing through which carriers are transmitted, an air valve for controlling the passage of air through said tubing, mechanism operating independently of variations in pneumatic pressure to open the valve upon the despatching of a carrier, and timing mechanism acting to control the closing of the valve, said valve having a casing with a chamber

therein which when said valve is closed is normally in communication with said transit tubing and with said tubing alone.

3. A pneumatic despatch tube system, having, in combination, transit tubing through which carriers are transmitted, means for exhausting air from said tubing, an air valve between the transit tubing and said means, electrically operated mechanism connected to open the valve, means for making and breaking the circuit for said mechanism when despatching the carrier, and a timing mechanism for automatically timing the closing of said valve, said valve when being closed, timed by said timing mechanism, and when open even but partly, affording communication between said air exhausting means and said transit tubing alone.

4. A pneumatic despatch tube system, having, in combination, transit tubing through which carriers are transmitted, an air valve for controlling the passage of air through said tubing, an exhaust device, means operating independently of the exhaust device for opening the valve upon the despatch of a carrier and a timing mechanism for automatically controlling the closing of the valve, said valve when being closed, being timed by said timing mechanism, and when open even but partly, affording communication between said air exhausting means and said transit tubing alone.

In testimony whereof I affix my signature, in presence of two witnesses.
